VENT PLUG

Joseph Lester Woodbridge, Philadelphia, Pa., assignor to The Electric Storage Battery Company, Philadelphia, Pa., a corporation of New Jersey

Application November 24, 1933, Serial No. 699,500

3 Claims. (Cl. 136—178)

The subject of my invention is a novel vent plug for storage batteries. This novel vent plug includes a valve member seat, a valve member containing a fluid and having flexible walls 5 of which one confronts said valve seat, and a weight mounted for rocking movement so that, upon tilting of the storage battery, the weight acts upon the fluid and moves the flexible wall confronting the valve seat so as to close the 10 valve against the valve member seat.

For a further exposition of my invention, reference may be had to the annexed drawing and specification at the end whereof the novel features will be specifically pointed out and claimed.

15 In the drawing:

Figure 1 is a vertical cross-section through my device; and

Figure 2 is a vertical cross-section through a modification of my device.

20 In Figure 1, the numeral 1 represents a portion of the cover of a storage battery in which is provided a cylindrical vent opening 2 passing through a boss 3 on the upper side of the cover and another boss 4 on the lower side of the cover.

25 The inner wall of the boss 3 is provided with screw-threads 5, with which corresponding external screw-threads of the vent plug 6 engage. The vent plug 6 has an internal chamber 7, closed by a cap 8, having a depending vent duct 9 communicating with the chamber 7 through openings 10, and providing a space 11 between the walls of the vent duct 9 and the walls of the vent plug 6, to retain any liquid which may escape from the cell when the latter is in an inverted position. The vent plug 6 is provided with a funnel-shaped orifice 12 communicating with the interior of the cell through the vent 35 passage 13. The vent plug 6 is provided with a lower cylindrical extension 14, having an internally projecting ledge 15 at its lower end upon which the weighted member 16 is supported by means of the umbrella-shaped top portion 17. This top portion 17 has an approximately spherically-shaped upper surface.

40 Within the depending cylinder 14, and above the weighted member 16 and below the orifice 13, is shown a valve member in the form of a hollow drum, having cylindrical walls 19, an upper head or diaphragm 20 of soft rubber, and a lower head or diaphragm 21 of soft rubber. This drum is liquid-tight and is filled with a suitable liquid, preferably a heavy liquid such as mercury. This drum is supported by means 45 of a collar 22 provided on the outer surface of

the cylindrical wall 19, which rests on a ledge 23 on the inner wall of the depending cylinder 14. When the cell is in its upright position, the weighted member 16 and the diaphragms 20 and 21 will assume the positions shown by the full lines in the drawing. The orifice 13 will therefore be open at the bottom, permitting any liquid, which may have collected in the chamber 7, to drain back into the cell, flowing over the top of the diaphragm 20 and down through the slots 24 in the cylindrical wall 14.

When the cell is tilted from its vertical position through a sufficient angle, the weighted member 16 will assume the position shown by the dotted lines 25 and the head 17 will rise, 15 pushing the lower diaphragm 21 upward into the position shown by the dotted lines 26, and, by reason of the incompressibility of the liquid in the drum, the upper diaphragm 20 will be raised to the position shown by the dotted lines 27, thus closing the orifice 13 and preventing the escape of liquid from the cell. When the cell is restored to its normal vertical position, the parts will assume the positions shown by full lines in the drawing, thus opening the orifice 13 and permitting the escape of any gases which may be developed in the cell such as those produced during the charging period.

45 In Figure 2, I have shown a modification in which the drum-like valve member is in the form of an inverted bag or sack 18, made of flexible material such as soft rubber and filled with a liquid such as mercury. The bag or sack 18 has a depending orifice or neck 30 which is forced over the head 31 of the member 32 which may be made of heavy material such as lead alloy, the joint between the neck 30 and the head 31 being sealed so as to be liquid-tight in any suitable manner as by the use of cement. The member 32 has a downwardly projecting support 33 whose point 34 rests in the apex of a conical cavity in the top of the weighted member 35. This weighted member is supported, as in the construction shown in Figure 1, by the inwardly projecting ledge 15. When the cell is tilted from its vertical position, the weighted member 35 will rock into the position shown by the dotted lines 36, causing the point 34 to be raised in an axial direction by reason of the fact that this point lies just below the plane of the supporting ledge 15. 50 This upward motion of the point 34 will cause the lower head of the valve member 18 to be raised, producing a corresponding rise in the upper head 20a, which will then assume the position shown by the dotted lines 21a, closing the 55

orifice 13 and preventing the escape of liquid from the cell.

While a non-compressible liquid is preferable for filling the valve member, a compressible fluid such as air may be used, requiring a somewhat greater displacement of the weighted member 16 to produce the same effect.

One of the important advantages of the construction disclosed lies in the fact that, when pressure is applied to the fluid in the hollow valve member, it is distributed over the entire surface of the flexible wall which confronts the valve seat, causing this flexible wall to fit into any irregularities in the surface of the valve seat, and thus effectively prevent any leakage of liquid when the cell is inverted. Any fluid, such as air or water or mercury, or even a semi-fluid or viscous material such as glycerine or light grease, would be effective for this purpose.

20 I do not intend to be limited in the practice of my invention save as the scope of the prior art and of the attached claims may require.

I claim:

1. In combination in a non-spill venting device for a vessel adapted to contain liquid, a valve seat surrounding a vent opening, a hollow valve member filled with non-compressible liquid and having pliable walls of which one confronts but is normally out of contact with the valve seat, 30 and means adapted when the vessel is tilted from

its normal position to displace another of said walls to cause the liquid within to force the first-mentioned wall against the valve seat, thereby to close the duct.

2. In combination in a non-spill venting device 5 for a vessel adapted to contain liquid, a vent duct terminating below in a valve seat, a hollow valve member filled with non-compressible liquid and having pliable walls whereof one confronts but is normally out of contact with the valve seat, 10 an annular inwardly projecting ledge below the valve member, and a weighted member supported on the ledge and adapted, when the vessel is tilted, to be displaced, thereby displacing another of the pliable walls of the valve member to cause 15 the liquid within to force the first-mentioned pliable wall against the valve seat, thereby to close the duct.

3. In combination in a non-spill venting device 20 for a vessel adapted to contain liquid, a valve seat surrounding a vent opening, a hollow valve member filled with incompressible liquid and having a pliable wall confronting but normally 25 out of contact with the valve seat, and means adapted when the vessel is tilted from its normal position externally to cause the liquid within said valve member to force the pliable wall against the valve seat, thereby to close the vent opening.

JOSEPH LESTER WOODBRIDGE. 30
